1

This invention relates to remote indicating systems and particularly to radio telemetering systems.

Certain telemetering systems are of the type in which a cyclically pulsed transmitter sends out spaced pulses of varying length thereby to transmit meter indications of varying values. The pulses upon being received, are amplified and then limited to a constant amplitude so that the length of each pulse is the sole variable, thus eliminating the detrimental effects of fading, interference, variations of equipment performance and other factors ordinarily affecting the accuracy of transmission and reception of the signal.

An object of the present invention is to provide a system of the aforesaid character having incorporated therein various improvements which further insure the accuracy of operation and the reliability of the system in service.

More specifically, the objects of this invention include the provision of better means of pickup from the transmitting instrument, more accurate pulsing means at the transmitting end, improved limiting means at the receiving end, more stable cyclic control of pulsing, multiple-channel pulsing, impedance matching or decoupling tubes between various functional circuits to prevent interaction, more stable pulse extinguishing circuits, improved stability with respect to supply voltage variations, temperature compensation features, and independent minimum and maximum pulse length adjustments.

Various other objects, advantages and features will become apparent from the following specification when taken in connection with the accompanying drawings wherein a certain preferred embodiment is set forth for purposes of illustration.

In the drawings, wherein like reference numerals refer to like parts throughout:

Fig. 1 is a block diagram of the transmitting equipment in a telemetering system constructed according to and embodying the principles of the invention;

Figs. 2A to 2H, inclusive, are diagrammatic representations of various time-voltage relationships or oscilloscope patterns drawn to the same time scale and pertaining respectively to circuit components shown in Fig. 1;

Fig. 3 is a schematic diagram of a portion of the transmitting apparatus;

Figs. 4A, 4B and 4C are oscilloscope patterns of various control voltage variations under different operating conditions;

Figs. 5A, 5B and 5C, taken together, constitute

2

a schematic diagram of the transmitting apparatus; and

Fig. 6 is a schematic diagram of the receiving equipment of the system.

The present invention is adapted for use in a system comprising a transmitting section, a receiving section and a radio link between said sections. The transmitting section will be described first. This section is associated with one or 10 more transmitting instruments or meters such as the aircraft instrument 8, Fig. 1. The reading or indication of each transmitting instrument usually determines the setting of an associated control potentiometer 10, Figs. 3 and 5B. In most instances it will be preferable to couple the potentiometer to the meter through the medium of a suitable torque amplifier or synchro arrangement 9, Fig. 1. The transmitting section functions to convert the various potentiometer settings into radio signals in the form of spaced pulses having variable pulse lengths according to the values represented by the potentiometer settings. Where the transmitting instrument is of such a character that it produces its own output voltage, such voltage is used to control the formation of the data-transmission pulses in similar fashion, as will be described.

Referring to Fig. 1, a low-frequency oscillator 12 having a sine-wave output, as shown in Fig. 30 2A, of approximately 10 cycles per second controls the periodicity of the pulses transmitted by the system. The oscillator 12 is coupled by an impedance matching tube 14 to a blocking oscillator 16, the latter oscillator being a device for producing extremely short, timed pulses as shown in Fig. 2C. The effect which this has on the output voltage of tube 14 is shown in Fig. 2B. The timed pulses, Fig. 2C, are effective to trigger a sawtooth generator 18 having an output as represented in Fig. 2D. A portion of this output is applied through an impedance matching tube 20 to one or more square wave generators as 22, there being one such generator for each telemetering channel. Another portion of the sawtooth output is utilized to time the operation of an extinguishing pulse generator 24 which produces extinguishing pulses as shown in Fig. 2E.

As will be explained in greater detail herein-after, each pulse of the square wave, Fig. 2F, is initiated at a selected time in the pulsing period corresponding to the indication of the transmitting meter 8, and is terminated at the end of the period or cycle by an extinguishing pulse, Fig. 2E. A switch tube 26 controlled by generator 55 22 applies variable-length direct-current pulses,

Fig. 2G, to the control element of a buffer 28 that is interposed between a supersonic oscillator 38 and the transmitter 32. The oscillator 38 is a subcarrier generator, there being one such generator for each telemetering channel, and all of the generators operating at various supersonic frequencies to accommodate the maximum number of channels with minimum cross-channel interference at the receiving end. The output of the oscillator 38, after passing through the buffer 28, has a waveform as shown in Fig. 2H, consisting of pulses of supersonic-frequency oscillations having constant periodicity and variable pulse length. These pulses are utilized to modulate a transmitter 32 which feeds an antenna 34 for transmitting the meter data by radio to the receiving apparatus. Preferably the transmitter 32 is of the frequency-modulated type and serves to transmit the signals in all telemetering channels on a common carrier frequency.

Referring now to Fig. 5A, the low-frequency oscillator 12 establishes the controlling frequency for all constant-periodicity functions of the transmitting section. Accuracy of data transmission dictates that this oscillator be unusually stable as to frequency regardless of changes in the supply voltages and temperature. To stabilize the oscillator 12 against supply voltage fluctuations the anode of the tube 38 in the oscillator 12 is connected through a resistor 40 to the positive terminal of a voltage regulator tube 42, Fig. 5B, that is connected through certain resistors (to be described later) to a voltage source such as the generator 36, Fig. 5A. The voltage regulator 42 has a stabilizing effect upon the anode voltage supplied to the tube 38. Further stabilization with respect to supply voltage is accomplished by properly proportioning the relative values of the anode resistor 40, series grid resistors 44 and 46, and grid capacitor 48. Frequency stability with respect to temperature is obtained by making the resistors 44 and 46 of conducting materials having different temperature coefficients. Resistor 44 is wound of wire having a very slight temperature coefficient of resistance and may be considered to remain essentially constant in resistance. Resistor 46 is of a carbon composition having a negative temperature coefficient of resistance. The resistors 44 and 46 tend to produce shifts of oscillator frequency in opposite directions when there is a change in the temperature of the frequency-determining components comprising the capacitor 48 and tapped inductance 50. By selection of suitable relative values of resistors 44 and 46 the frequency of the oscillator 12 can be maintained essentially constant over a selected temperature range.

An impedance matching or decoupling cathode follower tube 14 is interposed between the low-frequency oscillator 12 and the blocking oscillator 16. The anode voltage for tube 14 is obtained from a voltage regulator tube 10, Fig. 5A. Cathode resistor 54 normally biases the grid of tube 14 so that this tube operates on the negative portion of the grid voltage-plate current characteristic whereby the action of oscillator 16 does not reflect any change of load back to the oscillator 12. Voltage divider resistors 56 and 58 have relative values such as to produce the desired amplitude of low-frequency voltage applied to the grid of tube 14.

The blocking oscillator 16 includes a tube 60 and a transformer 62 and serves to produce extremely short, timed pulses of voltage for accurately controlling the firing of a gas tetrode or

thyatron 64, Fig. 5B, in the sawtooth oscillator 18. The anode of tube 60, Fig. 5A, is connected through the primary 66 of transformer 62 and a decoupling resistor 68 to a voltage regulator tube 70 that is energized by the high-voltage source 36. The junction of primary 66 and resistor 68 is connected to ground through a resistor 72 and capacitor 74. The voltage appearing across the cathode resistor 54 of the cathode follower 14 is applied through a secondary 76 of the transformer 62 and a capacitor 78 to the grid of the blocking oscillator tube 60, this grid being connected to ground through a resistor 80.

The connections of transformer 62 are so phased with respect to the grid and anode of tube 60 that the oscillator 16 tends to produce sustained oscillations. The oscillator circuit elements are so adjusted that the natural frequency of oscillator 16 is slightly lower than the controlling frequency of the oscillator 12. When the sine-wave voltage applied to the grid of tube 60 attains a predetermined value, the tube 60 conducts, causing anode current to flow through the primary 66. The instant that anode current starts to flow in the primary 66, secondary 76 produces a high-voltage pulse to charge the capacitor 78. The phase of this charge is such as to drive the grid of tube 60 in the far negative region, thus effectively cutting off the flow of anode current. The circuit is so arranged that an extremely short-duration voltage pulse appears across the cathode resistor 82 of the oscillator 16, as indicated in Fig. 2C. As the charge on capacitor 78 leaks off, the grid potential of tube 60 rises with the rise in the controlling sine-wave voltage until a condition of anode-cathode conduction again is established, whereupon the cycle is repeated. Thus, timed pulses of extremely short duration are produced at regular intervals as determined by the periodicity of the low-frequency oscillator 12.

The output pulses, Fig. 2C, of the blocking oscillator 16 are utilized to control the firing of a thyatron 64, Fig. 5B, in the sawtooth generator circuit 18. This sawtooth generator is adapted to furnish sawtooth pulses of maximum linearity as indicated in Fig. 2D, the repetition rate of the sawtooth pulses being controlled by the timing of pulses from the blocking oscillator 16. The values of capacitor 84 and resistor 86 are selected to allow operation on the steep portion of the charging characteristic of the timing capacitor 84. Anode voltage for the tube 64 is obtained through the resistor 86 from the voltage regulator tube 42.

Tube 64 is fired each time a pulse from the blocking oscillator 16 is impressed upon its control grid. Capacitor 84 thereupon discharges through the tube 64, this portion of the operation being represented by the vertical lines in the pattern of Fig. 2D. A sharp rise of potential therefore occurs across the cathode resistor 88 and is communicated to the grid of an extinguisher tube 90 in the extinguisher pulse generator 24. The function of this extinguisher will be explained more fully hereinafter. A capacitor 92 bypasses the resistor 88 to provide a low impedance path which facilitates the rapid discharge of timing capacitor 84. Voltage divider resistors 94 and 96 are selected for suitably biasing the grid of tube 90 and the cathode of tube 64.

Following the discharge of timing capacitor 84, upon termination of the firing pulse applied to the grid of tube 64, the capacitor 84 com-

mences to charge whereby a linearly increasing voltage appears on the anode of tube 64. This voltage is applied to the grid of the impedance matching tube 20 through a coupling capacitor 88. Tube 20 is arranged in a cathode follower circuit and functions as a low-impedance driver for furnishing sawtooth voltage to a number of square wave generators, such as 22, there being one such square wave generator for each telemetering channel that is to be utilized in the system. In the illustrated embodiment it is assumed that there are three telemetering channels, respectively, including the square wave generators 22, 100 and 102. Gas tetrodes or thyatron 104, 106 and 108 are included respectively in the generators 22, 100 and 102. The control grids of these thyatrons are connected respectively through decoupling resistors 110, 112 and 114 to the cathode of tube 20, whereby interaction between the square wave generators is minimized. The control grid of tube 104 also is connected through a coupling resistor 116 to the movable tap of the potentiometer 10, Figs. 5B and 3. It will be recalled that this potentiometer 10 has an operative connection through a servo-mechanism 9 or like device to a transmitting instrument such as meter 8, Fig. 1. One end of the potentiometer 10 is grounded while the other end is connected through a rheostat 118 and fixed resistor 120 to the anode of the voltage regulator tube 42, which in turn is connected through the series resistors 122, 124 and 126 to the high-voltage source 36, Fig. 5A.

Anode voltage for the tubes 104, 106 and 108, Fig. 5B, is obtained from the voltage regulator tube 52, Fig. 5A, through the secondary 128 of a pulse transformer 130, Fig. 5B. The primary 132 of transformer 130 is arranged to be energized by the output of the extinguisher tube 90 as will be explained. Isolating resistors 134, 136 and 138 are incorporated in the anode circuits of the square wave generator tubes to minimize interaction.

A simplified schematic diagram showing the pertinent components of the transmitting channel in which the square wave generator 22 is included is presented in Fig. 3. Omissions of circuit elements that are illustrated in Figs. 5B and 5C are indicated by dotted lines in Fig. 3. The cathode of tube 104 is connected to the movable tap of a potentiometer 140, one end of this potentiometer being connected through a resistor 142 to ground. The other end of the potentiometer is connected through a temperature-compensating combination of resistor 144 and resistor 146 to a junction 147 of resistors 122 and 124, Figs. 5A and 5B. This resistor pair serves to maintain operational stability with respect to temperature changes.

The general operation of the square wave generator 22 is such that a pulse is initiated by this generator when the combined potential of the sawtooth voltage and the steady voltage applied to the control grid of tube 104 attains the firing potential of this tube. The pulse thereafter is extinguished at a predetermined time whereupon the tube 104 is rendered nonconductive until its grid potential again is raised to the firing point. The potential E, Fig. 3, applied to the potentiometer 10 is adjusted by means of the rheostat 118, Fig. 5B, to give maximum pulse length for maximum setting of potentiometer 10, that is to say, for maximum reading of the transmitting instrument 8, Fig. 1. The cathode potentiometer 140 is adjusted for a minimum pulse

length corresponding to minimum setting of the potentiometer 10. The direct-current voltage V, Fig. 3, which varies with the setting of potentiometer 10, is applied to the control grid of tube 104, while the sawtooth voltage from generator 18 (through the medium of the impedance matching tube 20) is superimposed on this direct-current voltage. This causes the grid voltage of the tube 104 to vary as shown, for example, in Fig. 4A, which illustrates the operation for a minimum pulse length. Starting from the level V determined by the setting of the potentiometer 10, the combined potential rises until the sawtooth pulse is terminated, whereupon the cycle is repeated. As the grid voltage reaches the firing point, the tube 104 suddenly draws anode current.

When each sawtooth pulse is terminated by the firing of the tube 64, the tube 90, which normally is biased to cut off by proper selection of values of the voltage divider resistors 148 and 150 controlling the cathode bias, suddenly becomes conductive and draws current through the primary 132 of the pulse transformer 130, discharging a capacitor 152. The resultant pulse in the secondary 128 of transformer 130 is of sufficient negative value to cancel the positive voltage normally supplied to the anode of tube 104. The design of the transformer 130 and associated circuits is such as to maintain the negative pulse from secondary 128 for sufficient duration to allow complete deionization of the tube 104 to take place, thereby extinguishing the pulse furnished by the square wave generator 22. The wave form of the square wave generator output is as shown in Fig. 2F or in Fig. 3. After the grid of tube 90 has been returned to its normal cut-off potential when tube 64 ceases conducting, capacitor 152 is recharged from the positive voltage source 36 through a resistor 153, Fig. 5A.

The length L of the square wave pulse is dependent upon the setting of potentiometer 10. Thus, referring to Figs. 4A, 4B and 4C, an initially low setting of the potentiometer 10 lowers the starting level V of the sawtooth voltage variation so that a relatively long time is required to attain the firing voltage F of the tube. Under these conditions, the tube is fired late in the pulsing period and a pulse of short length L is produced. For a high setting of potentiometer 10 the starting voltage V is raised so that the firing voltage F is attained relatively early in the period, producing a pulse of greater length L, as shown in Fig. 4C. For an intermediate setting of potentiometer 10, an intermediate pulse length L is produced as indicated in Fig. 4B.

The pulse voltage that appears at the anode of tube 104 is reduced to a suitable level by voltage divider resistors 154 and 156, Fig. 5B, and is applied to the grid of the switch tube 26, Figs. 5C and 3. The voltage pulse furnished by the generator 22 to the grid of tube 26 is of negative sign, as indicated in Figs. 2F and 3. The tube 26 normally is maintained in a cut-off condition while the square wave generator tube 104 is conducting, by having its cathode sufficiently positively biased by the voltage drop through divider resistors 158, 160 and 162. The anode of tube 26 is connected through a resistor 164 to the junction 165 of resistors 158 and 160. When the tube 26 is in its non-conducting state, the buffer 28 functions to pass the supersonic oscillations generated by the oscillator 30. This oscillator is of conventional design and is arranged so that a portion of its output voltage is fed through a

coupling capacitor 166 to the grid of the buffer tube 168. Self-bias is maintained on the tube 168 by a cathode resistor 110. The anode of switch tube 26 is connected to the grid of buffer tube 168 through an isolating resistor 172. A parallel tuned circuit 174 is interposed between the resistors 170 and 160 in the cathode circuit of tube 168. This tuned circuit is resonated at the supersonic frequency produced by oscillator 30 and minimizes the effects of stray signals from adjacent channels. The anode of tube 168 is supplied with operating voltage by the regulator tube 178.

When the square pulse from generator 22 is terminated, the grid of tube 26 rises in potential to a point where conduction takes place through this tube. Anode current drawn by the tube 26 produces a voltage drop in the resistor 164 which is effective to reduce the grid potential of tube 168 to the cut-off point, whereupon buffer 28 ceases passing the telemetering signal from the supersonic oscillator 30. When the square wave generator tube 104 again conducts and switch tube 26 is cut off, the grid potential of tube 168 rises for enabling the buffer 28 again to pass the supersonic signal. The output of switch tube 26 comprises positive pulses, Fig. 2G, each having a length commensurate with the length of the controlling pulse furnished by the square wave generator 22. As the tube 26 switches the conduction of tube 28 on and off, it may be aptly termed a switch tube. The signal passed by the buffer 28 comprises a pulsed supersonic-frequency signal as shown in Fig. 2H. This latter signal is utilized as a subcarrier for modulating the frequency-modulation transmitter of the system.

There has been described a channel of the telemetering system including square wave generator 22, Figs. 1, 3 and 5B, switch tube 26, Fig. 5C, supersonic oscillator 30 and buffer 28. Other channels are of similar construction and arrangement; for instance, the channel which includes the square wave generator 102, Fig. 5B, may be controlled by a potentiometer 180 having an operative connection with a transmitting instrument similar to the meter 8, Fig. 1. A supersonic oscillator 182, Fig. 5C, having a frequency different from that of the supersonic oscillator 30, is provided for the channel under consideration. A switch tube 184 and buffer 186 function to initiate and terminate pulses of supersonic-frequency oscillations which are fed to the transmitter. All of the channels feed their output to a common output mixer tube 190, Fig. 5C, through coupling capacitors as 192 and isolating resistors as 194. The grid potentiometer 196 is provided to adjust the composite signal level for proper operation of tube 190. Output transformer 198 matches the output tube 190 to the transmission line leading to the modulator section of the transmitter. A balanced line has been found desirable for eliminating any possible stray pick-up from nearby equipment. Cathode resistor 200 of tube 190 and bypass capacitor 201 produce the required operating bias for tube 190. The anode of tube 190 is connected through the primary of transformer 198 and an isolating resistor 202 to the high-voltage source 36, Fig. 5A. A capacitor 204 is provided to bypass the alternating-current component in the output of tube 190. With the exception of the output mixer tube 190, all of the tubes illustrated in Fig. 5C are supplied with anode voltage from the regulator tube 178.

There may be instances when it is desirable to control a telemetering channel by a transmitting instrument which furnishes its own controlling voltage. Such an instrument would be a tachometer including a direct-current generator as 208, Fig. 5B, having an output voltage proportional to its rotational speed. In the system as illustrated herein the tachometer generator 208 is associated with the telemetering channel which includes the square wave generator 100. One terminal of the generator 208 is grounded and the other terminal is connected in series through resistor 210, potentiometer 212 and resistor 214 to ground. Maximum pulse length adjustment is effected by the potentiometer 212, the slider of which is connected through a resistor 216 to the control grid of tube 106, while minimum pulse length adjustment is effected by a potentiometer 218, the slider of which is connected to the cathode of tube 106. One side of potentiometer 218 is connected to ground through a resistor 220 while the other side thereof is connected through the temperature-compensating resistors 222 and 224 to the junction 225 between the resistors 124 and 126, Fig. 5A.

The output of square wave generator 100, Fig. 5B, through the medium of a switch tube 228, Fig. 5C, controls the passage of supersonic telemetering pulses from an oscillator 230 by a buffer 232 in substantially the same manner as previously described in connection with other telemetering channels. The output of the tachometer-controlled channel is fed to the mixer tube 190. It will be noted that the length of pulse furnished by this channel is determined not by the setting of an element such as a potentiometer, but by the magnitude of the controlling voltage developed by the tachometer generator 208. In its essential aspects, however, operation is no different from that described above.

A high degree of accuracy in the control of pulse length requires that compensation be provided to offset changes in supply voltage. The use of voltage regulator tubes as 42, Fig. 5B, assists greatly to stabilize the voltage. However, because such devices do not operate perfectly, additional means are provided to obtain the results desired. Thus, in the case of the first telemetering channel described above, the string of resistors 142, 144 and 146 is returned to the junction 147 between resistors 122 and 124 intermediate the unregulated voltage supply source 36 and the regulator tube 42. With this arrangement a change in supply voltage will affect the cathode potential of tube 104 to a greater extent than it will the grid potential of this tube. This serves to nullify the effect of such grid potential variation and also to compensate for the change of slope of the sawtooth voltage rise during the charging of timing capacitor 84. In the case of the tachometer-controlled telemetering channel, the connection of the resistor string 220, 218, 222 and 224 to the junction 225, Fig. 5A, has a similar compensating function.

The frequency-modulated signal which is transmitted from the antenna 34, Fig. 1, is demodulated at the receiving end of the system, and the demodulated telemetering signal is fed to the input terminals of an impedance-matching transformer 231, Fig. 6. The secondary of transformer 231 supplies pulsed telemetering signals of all the supersonic frequencies used for transmission to selective circuits in the various receiving channels. Fig. 6 schematically illus-

trates one channel only of the receiving equipment. As there shown, each channel is provided with a selective circuit 233 and an isolating resistor 234, which function to select a particular telemetering signal corresponding to such channel. The signal which is passed by the selective circuit has a wave form similar to that shown in Fig. 2H, comprising spaced pulses of supersonic-frequency oscillations. An amplifier 236 amplifies this signal and feeds it to a rectifier 238 through a coupling capacitor 240. An inductance 242 affords a high impedance between the cathode of rectifier 238 and ground for the telemetering signal, yet provides a low-resistance direct-current path to ground in order to maintain proper rectified direct-current voltage across the resistors 244 and 246 in the output circuit of rectifier 238. Filter capacitors 248 and 250 aid to remove the supersonic-frequency component from the output of rectifier 238.

A voltage regulator tube 252 and regulating resistor 254 are arranged to supply a substantially constant direct-current voltage to a switch tube 256. The anode of tube 256 is connected directly to the anode of a control tube 258 and is also connected through a rheostat 260 and resistor 262 to the anode of the regulator tube 252. The tube 256 is of the gas-filled regulator type designed to regulate, for example, at 105 volts, whereas tube 252 regulates at a higher voltage, such as 150 volts. The cathode of tube 256 is connected through the receiving instrument, such as meter 264, to ground.

The rectified and filtered direct-current output voltage from the rectifier 238 is applied to the grid of the control tube 258. This output voltage is in the form of a negative pulse when a telemetering signal pulse is being received by the channel. The grid of tube 258 is swung into the cut-off region by the pulse, thus stopping the flow of anode current through this tube. Under these conditions, the tube 256 passes current at substantially constant voltage through the meter 264. When the pulse is terminated, the tube 258 again conducts current, thereby reducing the potential across the tube 256 below the conducting value. 256 therefore ceases conducting and stops the flow of current through the meter 264.

The current which passes through the meter 264 is in the form of direct-current pulses having substantially constant amplitude and variable pulse length. Preferably the meter 264 is a simple D'Arsonval type of instrument in which the pointer deflection is proportional to the average energy in the deflecting coil. Inasmuch as pulse length is the only variable, the meter deflection is a measure of the pulse length and therefore of the quantity represented thereby. The rheostat 260 is adjusted so that the meter 264 has maximum reading when a pulse of maximum length is received. The meter has a calibrated zero position corresponding to minimum pulse length, and all intermediate readings will be proportional to transmitted pulse length.

It will be seen from the foregoing that the invention provides a radio telemetering system having numerous advantageous features. The various pulsing devices at the transmitting end are highly accurate and dependable in operation. Stabilization against supply voltage fluctuations is provided wherever it is materially conducive to increased reliability. Temperature compensation is provided wherever changes in temperature are apt to have detrimental effects on the accuracy of the system. The square wave genera-

tors are controlled by highly stabilized pulse-initiating and pulse-terminating means. This system will accommodate multiple channels without undue interference between channels.

5 Impedance matching and decoupling tubes are employed wherever there is a likelihood of interaction between functional circuits. Independent minimum and maximum pulse length adjustments are afforded by arrangements such as 10 those including the potentiometers 140 and rheostat 118, Fig. 5B. The receiving section has an extremely simple, but very effective, limiting means comprising the control tube 258 and regulator tube 256. These and other features combine to render a marked advancement in the art of telemetering.

It is obvious that various changes may be made in the specific embodiments set forth for purposes of illustration without departing from the 20 spirit of the invention. The invention is accordingly not to be limited to the specific embodiments shown and described, but only as indicated in the following claims.

25 The invention is hereby claimed as follows:

1. In a telemetering system for transmitting data by electrical pulses of variable length under the control of a transmitting instrument, a variable potential source controlled by said instrument, a sawtooth generator including a gas-filled electron tube and a timing capacitor having a discharge path through said tube when said tube is conductive, stabilized-frequency means for periodically rendering said tube conductive, a square wave generator arranged to be biased by said variable potential source, circuit means for applying the output of said sawtooth generator to said square wave generator, said square wave generator being effective in response to a particular 30 value of applied potential as determined by the bias voltage for initiating a control pulse, and an extinguishing pulse generator including a normally charged capacitor, an electron tube biased by said sawtooth generator and effective to discharge said normally charged capacitor concurrently with each discharge of said timing capacitor, and a pulse transformer having a primary arranged in the discharge path of said normally charged capacitor and a secondary arranged in the operating circuit of said square wave generator.

50 2. In a radio telemetering system, a transmitting instrument, a sawtooth generator, a stabilized-frequency oscillator controlling said sawtooth generator to fix the periodicity thereof at a substantially constant value, a thyratron having a predetermined firing voltage, means applying to said thyratron a voltage of constant selected value as determined by the condition of 55 said transmitting instrument together with a voltage of continually increasing value derived from said sawtooth generator, an extinguishing pulse generator controlled by said sawtooth generator for periodically interrupting the conduction 60 of current by said thyratron, a telemetering signal generator, and electronic switching means including a first tube controlled by said thyratron whereby said first tube is cut off when said thyratron is conducting, and a second tube so arranged in relation to said first tube and said signal generator that telemetering signal is passed by said second tube when said first tube is cut off.

65 3. In a radio telemetering system for transmitting pulsed data signals under the control of 70 a transmitting instrument, a pulse generator in-

cluding an electron tube normally maintained in a non-conductive condition and responsive upon application thereto of a grid potential of predetermined value to conduct current, a first potentiometer settable under control of said transmitting instrument, said electron tube having a control grid connected to a movable contact of said first potentiometer, a rheostat in series with said first potentiometer, a regulated voltage source for applying a substantially constant voltage across said rheostat and said first potentiometer, a second potentiometer, said electron tube having a cathode connected to a movable contact of said second potentiometer, a source of operating voltage for said tube, resistance means connecting said second potentiometer to said operating voltage source, cyclic operating means for applying to said control grid a voltage having a sawtooth wave form whereby the total voltage applied to said control grid is the sum of the sawtooth voltage and the voltage derived from said first potentiometer, and other cyclic operating means operating in timed relation with said first cyclic operating means to interrupt the supply of operating voltage from said source thereof, said rheostat being adjustable to effect production by said pulse generator of a pulse having maximum predetermined length for maximum position of said transmitting instrument, said second potentiometer being adjustable to effect production by said pulse generator of a pulse having minimum predetermined length for minimum position of said transmitting instrument.

4. In a radio telemetering system for transmitting variable-length data pulses, a square wave generator including a thyratron, cyclically operating means for impressing periodically on the control grid of said thyratron a substantially linearly varying voltage, means for adjusting the quiescent potential of said grid to a selected value, means for adjusting the quiescent potential of the cathode of said thyratron to a selected value, and temperature-compensating means in circuit with said thyratron to maintain the difference in said quiescent potentials substantially constant irrespective of temperature changes within a given range.

5. In a radio telemetering system for transmitting data by pulses of variable length, a pulse generator including an electron tube having an anode, a cathode and a control grid, a source of operating voltage for said electron tube, a voltage regulator tube, a resistance element connecting said voltage regulator tube to said source, means connecting the grid of said electron tube to said voltage regulator tube, means applying a continually varying voltage on said grid, said electron tube responding when the difference in potential between the grid and cathode thereof attains a predetermined value to initiate a pulse by said pulse generator, and means connecting the cathode of said electron tube to a point of intermediate resistance on said resistance element whereby fluctuations in the voltage supplied by said source produce compensating changes of potential at the grid and cathode of said electron tube.

6. In a radio telemetering system having means for transmitting pulsed radio signals and a receiver including means for demodulating such radio signals, means for amplifying the demodulated signals, means for rectifying the demodulated signals passed by said amplifying means, means including a voltage regulator tube for limiting the amplitude of rectified signal in the

output of said rectifier, and a direct-current measuring instrument substantially in parallel with said regulator tube.

7. In a radio telemetering system having means for transmitting pulsed radio signals and a receiver including means for demodulating such radio signals, means for amplifying the demodulated signals, means for rectifying the demodulated signals passed by said amplifying means, a gas-filled regulator tube having a required minimum value of operating voltage, a regulated source of direct-current voltage, resistance means connecting said regulator tube to said voltage source, a direct-current meter connected in series with said regulator tube, and means including an electron tube controlled by said rectifier and connected in circuit with said source and said regulator tube for controlling the voltage across said regulator tube in response to the received signals, said electron tube being in parallel with said regulator tube and said meter.

8. The combination set forth in claim 7, wherein said electron tube is arranged to draw substantially no current from said source when a signal pulse of at least a predetermined minimum value is received, said electron tube being also effective in the absence of a signal pulse to draw sufficient current to reduce the voltage across said regulator tube below the required minimum value thereof.

9. A radio telemetering system comprising a plurality of square wave generators each including a thyratron, a sawtooth generator driving all said square wave generators, a stabilized-frequency oscillator driving said sawtooth generator, individual adjusting devices for said square wave generators whereby the respective firing times of said thyratrons are selected separately, an extinguishing pulse generator operating in timed relation with said sawtooth generator for periodically and simultaneously extinguishing all said thyratrons, a plurality of telemetering signal generators of preselected different frequency each in a separate transmitting channel, a plurality of electronic switching devices respectively controlling said transmitting channels and arranged to respond respectively to said square wave generators, frequency-selective filters to prevent interaction between said transmitting channels, a radio transmitter, a common mixer stage for applying the outputs of all said channels as modulating signals to said transmitter, and a radio receiver having associated therewith a plurality of receiving channels corresponding respectively to said transmitting channels.

10. A radio telemetering system as set forth in claim 9, wherein each of said receiving channels comprises a frequency-selective filter, an amplifier, a rectifier, a limiter for controlling the amplitude of signal passed by said rectifier, and a direct-current meter in circuit with said limiter.

11. In a telemetering system having means for transmitting pulsed signals, receiving means including means to amplify the signals, means including a voltage regulator tube to limit the amplitude of the amplified signals, a second voltage regulator tube, and a measuring instrument in series with said second tube.
